UNITED STATES PATENT OFFICE.

WALTER O. JOHNSON, OF CHICAGO, ILLINOIS, ASSIGNOR TO T. JOHNSON COMPANY, OF CHICAGO, ILLINOIS, A CORPORATION OF ILLINOIS.

APPARATUS FOR AND PROCESS OF TRUING COOPERS' TRUSS HOOPS.

Application filed July 7, 1921. Serial No. 432,893.

To all whom it may concern:

Be it known that I, WALTER O. JOHNSON, a citizen of the United States, residing in Chicago, in the county of Cook and State of Illinois, have invented a new and useful Improvement in Apparatus for and Processes of Truing Coopers' Truss Hoops, of which the following is a specification.

This invention relates in general to the truing of coopers' truss hoops and, while the apparatus set forth as embodying the invention is particularly adapted for the truing of coopers' truss hoops after they have become distorted in service, it will be readily manifest that the invention has valuable use in connection with the accurate truing of such devices by the manufacturer originally supplying them.

The invention relates also to both an apparatus and a process.

A principal object of the invention is the provision of an apparatus, for truing coopers' truss hoops, which will be of simple operation and by reason of its construction insure accurate results without the necessity of particular care in the manipulation of the apparatus or the need of skilled mechanics for its operation.

Another important object of the invention is the provision of a retruing apparatus which will be of sufficiently simple and cheap construction to permit its installation in coopersing establishments of relatively small capacity.

Another important object of the invention is the provision of an apparatus of this kind which will be capable of manual operation, although of course from many aspects of the invention power means may be desirably employed.

Another important object of the invention is the provision of an apparatus of this character which will consist of few parts, all inherently strong and substantial and unlikely to require frequent repair or replacement, and which will not require any adjustment in the operation.

Another and highly important object of the invention is the provision of an apparatus of this kind, which, by a simple substitution, may be adapted to true coopers' truss hoops of different diameters.

Numerous other objects and advantages of the invention will be apparent as it is better understood from the following description,

which, taken in connection with the accompanying drawings discloses a preferred embodiment thereof.

Referring to the drawings,

Figure 1 is a side elevation of a cooper's truss truing apparatus in which my present invention is embodied;

Fig. 2 is a top plan view thereof;

Fig. 3 is a section taken on the line 3-3 of Fig. 2; and

Fig. 4 is a perspective view of one of the truss hoops.

In describing my present invention I will first describe the apparatus, shown on the drawing, in which it is at present preferably embodied. Referring to this apparatus, reference character 11 indicates a strong, rigid bed supported upon three or more legs 12. At each side the bed is provided with bosses 13 in which are mounted posts 14 carrying an arbor 15 at their tops.

Referring now to Fig. 3 it will be noted that the bed 11 is provided with an upstanding enclosed flange or wall 16 and with a central opening or aperture 17 adapted to be closed by a plug 18. If desired a strengthening web or depending flange 19 may be provided. A press screw 21 is threadedly engaged in a threaded bearing plug 22 in the arbor 15 and this arbor may consist of two main channel members 23 connected together by the plug 22 and by end connecting plugs 24 through which the posts 14 extend. A head or plunger member 25 is mounted upon the lower end of the screw 21, this screw having an enlarged lower end 26 fitting in an opening 27 in the hub 28 of the head or plunger 25 and being held against independent longitudinal movement of the screw by a pusher 29 locked in place by a set screw 31. This permits of the rotation of the screw independently of the press head. The press head includes in addition to the hub 22 a number (four in the present instance) of arms or spokes 32 terminating in an integral annular rim or body 33. The arms 32 and rim 33 are slotted at 34 to receive screws or other fastening devices 35 which carry a truing member 36, said fastening devices being adjustable in said slots to permit the use of truing members of different diameters. This truing member is tapered on its outer face and is preferably of annular form and has an outwardly extending flange 37 at its top adapted to form a stop for the truss

100. 105. 110.

hoop in the action of said truing member. The truss ring is indicated by reference character 38 and it will be noted that it has a tapering inner face, the outer face of the 5 truing member 36 having substantially the taper of this inner face of the truss ring. The width of the tapered face of the truing member is preferably exactly equal to the width of the tapered face of the ring.

- 10 In truing the ring, the ring is first heated to a cherry red and then placed over the truing member 36 and the press screw screwed down until the ring is forced up against the shoulder 37 throughout its entire circumference. Preferably while this pressure is still upon it, water or other cooling medium is poured upon the bed and within the wall 16 so that this bed and wall constitute a tank. In thus cooling or chilling 20 the truss ring it is further contracted and set in its trued condition.

It is thought that the invention, both as regards the process and the apparatus, will be understood from the foregoing description, and it will be apparent that various changes may be made in the form, construction and arrangement of the parts without departing from the spirit and scope of the invention or sacrificing all of its material 25 advantages, the form hereinbefore described being merely a preferred embodiment thereof.

I claim:

1. An apparatus for truing coopers' truss 35 hoops, comprising, a size determining means insertable into a hoop, clamping means for securing the hoop against axial movement, and means for shrinking the hoop against said size determining device.
2. An apparatus for truing coopers' truss 40 hoops, comprising, a form determining means insertable into a hoop, clamping means for securing the hoop against axial movement, and means for shrinking the hoop against said form determining device.
3. An apparatus for truing coopers' truss 45 hoops, comprising a size determining means insertable into a hoop, clamping means for securing the hoop against axial movement and providing space for radial truing movement of said hoop while clamped throughout its circumference, and means for shrinking the hoop against said size determining device.
- 55 4. An apparatus for truing coopers' truss hoops, comprising a tapered member adapted to enter into the hoop, a tank co-operating with said hoop, squeeze devices for producing relative movement between said member

and tank for forcing the hoop on to the 60 tapered member, said tank serving to receive liquid to contract the hoop about said tapered member after said hoop has been forced thereon.

5. An apparatus for truing coopers' truss 65 hoops, comprising a press bed, a press plunger, a tapered member carried by the press plunger and adapted to enter into a cooper's truss hoop to squeeze the same into place against said bed, and means associated 70 with said tapered member for limiting the truing movement of the hoop.

6. An apparatus for truing coopers' truss 75 hoops, comprising an annulus having a tapered surface substantially the width of the tapered surface of the hoop, a stop for limiting movement of the hoop along said tapered member, and compression means for forcing said hoop into engagement with said stop.

80 7. An apparatus for truing coopers' truss hoops, comprising a press bed, a press head, a truing tapered member carried by the press head and connected thereto, and connections between said press head and said truing member being adapted for various arrangement radially of said press head to permit of the use of truing members of different sizes.

85 8. The process of truing coopers' truss 90 hoops, comprising placing the same about a tapered member entering the truss hoop, forcing the truss hoop along said tapered member against a fixed stop to insure even movement throughout its circumference, and thereafter contracting said hoop.

9. The process of truing coopers' truss 100 hoops, comprising placing the same about a tapered member entering the truss hoop, forcing the truss hoop along said tapered member against a fixed stop to insure even movement throughout its circumference, and thereafter contracting said hoop while under the compressing pressure.

10. The process of truing coopers' truss 105 hoops, which consists in heating the hoop, positioning the hoop about a size determining device, confining the hoop against axial movement, and shrinking the hoop about said size determining device.

11. The process of truing coopers' truss 110 hoops, which consists in heating the hoop, positioning the hoop about a size determining device, confining the hoop against axial movement, and shrinking the hoop about said size determining device by means of a heat conducting liquid.

WALTER O. JOHNSON.
